CLAIM

The ornamental design for a front panel for a disc drive, as shown and described.

DESCRIPTION

FIG. 1 is a top plan view of a front panel for a disc drive showing our new design;

FIG. 2 is a bottom plan view thereof;

FIG. 3 is a front elevational view thereof;

FIG. 4 is a left side elevational view thereof;

FIG. 5 is a right side elevational view thereof; and,

FIG. 6 is a slightly reduced perspective view thereof. The housing is shown in broken lines for illustrative purposes only and form no part of the claimed design.

FIG. 1

FIG. 2

FIG. 3

FIG. 4
